UNITED STATES PATENT OFFICE.

EDWARD PERINA, OF PORT RICHMOND, NEW YORK.

FOUNTAIN-PEN CLIP.

Application filed July 7, 1923. Serial No. 650,085.

To all whom it may concern:

Be it known that I, EDWARD PERINA, a citizen of the United States, residing at Port Richmond, in the county of Richmond and 5 State of New York, have invented new and useful Improvements in Fountain-Pen Clips, of which the following is a specification.

This invention relates to manipulating devices.

More particularly the invention relates to devices especially adapted for use in conjunction with a plunger in the barrel of a fountain pen for effecting the movement of 15 the plunger in the filling of the barrel of the fountain pen with ink.

The type of fountain pen in conjunction with which the manipulating device of the present invention is used with is shown in 20 United States Patent #1,392,860, granted to me October 4th, 1921.

Some of the objects of the present invention are: to produce a more efficient and effectual manipulator of a character mentioned; to produce a manipulator which is of dual character in that it will serve for co-action with a plunger of a fountain pen for the filling of the pen and will also serve as a clip for the pen when not in use to 30 properly support the pen in a pocket.

With these and other objects in view, the invention resides in the particular provision, relative disposition and function of the parts hereinafter fully described, and illustrated in the accompanying drawing, in which:—

Figure 1 is a sectional elevation showing the use of the present invention.

Figure 2 is a sectional view through the manipulator.

Figures 3 and 4 are detail views.

Figure 5 is a detail perspective view of the free end of the manipulator.

As stated, the manipulator in the present invention is to be used in conjunction with a plunger of a fountain pen for filling the pen, and it is necessary that the manipulator be designed so as to be employed for rotating the plunger and for reciprocating the same the entire length of the barrel of the fountain pen, and to this end the manipulator has been constructed with necessary features and also embodies features by virtue of which the manipulator may be used as a clip when arranged on the end of the pen; one part of the manipulator being a

cap for the pen and serves as a supporting member for the other parts of the manipulator.

The manipulator of the present invention therefore, generally, comprises a supporting member or cap 10, a device 11 which is carried by the cap and which is directly connectable with the plunger P of the fountain pen and which also serves as a clip, and a device 12 which is carried by the cap 10 and serves to hold the device 11 in folded condition supplemented by a means 13. The supporting member or cap 10 is of the usual construction being open at one end and closed at the other and of cylindrical construction. The device 11 consists of a part 14 and a part 15 which are connected together for pivotal movement by a fastening element 16. The free end of the part 14 is connected to the cap 10 for pivotal movement by virtue of a fastening element 17. The free end of the part 15 has a hook 18 formed with a reduced finger 18'. The device 12 is cross sectionally U-shaped and the portion 19 thereof has a bendable member 20 by virtue of which the device 12 is attached to the cap, and the portion 21 of the device 12 has an enlargement 22. The device 12, as stated, serves for holding the device 11 in folded condition supplemented by the means 13. The means 13 consists of furcations 23 between which the finger 18' of the hook 18 may be disposed as shown in Figure 2. It is to be understood that the parts 14 and 15 are of resilient or flexible material and for this reason may be sprung beneath the portion 21 of the device 11 to be held thereunder by virtue of the enlargement 22. When so held in place the parts 14 and 15 are spaced with relation to each other and therefore one part may be flexed toward the other to release the same from the device 11. The fastening element 16 has a head 24 and co-acts with the wall 25 of the cap and thus affords a means for gripping the pocket when the pen with the manipulator thereon is arranged in the pocket.

When it is desired to manipulate the plunger of a fountain pen for the filling operation, the hook 18 is disengaged from the furcations 23 by flexing the part 15 and at the same time the part 15 is also brought out from beneath the portion 21 of the device 11. The parts 14 and 15 are then moved on their pivotal connections to bring the same in alignment, whereupon the hook 18

may be engaged with a portion of the parts, one of said pivoted parts pivoted to said supporting member and the other of said parts, having means engageable with a portion of said plunger to effect the movement thereof.

From the foregoing it will be manifest that there has been described a manipulator which is simple and durable in construction;

one which may be used for rotating and reciprocating an element requiring this action; and one which serves as a fastening clip as 45
10 added advantage.

What is claimed as new is:—

1. For use in conjunction with a plunger of a fountain pen, a supporting member, a device carried by said supporting member, 50
15 said device including a pair of pivotally connected links, the free end of one of said links being provided with furcations and pivoted to said supporting member, the free end of said other link being provided with
20 a means engageable with said plunger when the links are in extended position and means adapted for co-action with said furcation when the links are in folded condition.

2. For use in conjunction with a plunger 55
25 of a fountain pen, a supporting member, a device carried by said supporting member, said device including a pair of pivotally connected links, the free end of one of said links being provided with furcations and pivoted to said supporting member, the free end of said other link being provided with
30 a means engageable with said plunger when the links are in extended position and means adapted for co-action with said furcation when the links are in folded condition, and
35 means for locking said device in folded condition.

3. For use in conjunction with a plunger 60
40 of a fountain pen, a supporting member, a device carried by said supporting member, said device including pivotally connected

parts, one of said pivoted parts pivoted to said supporting member and the other of said parts, having means engageable with a portion of said plunger to effect the movement thereof.

4. For use in conjunction with a plunger of a fountain pen, a supporting member, a device carried by said supporting member, 55
50 said device including pivotally connected flexible parts, one of said parts pivoted to said supporting member and the other of said flexible parts having means engageable with a portion of said plunger to effect the movement thereof.

5. In a device of the class described, the combination with the plunger of a fountain pen, a supporting member, a foldable device pivotally mounted to said supporting member, co-acting elements formed on opposite ends of said foldable device for engagement with each other when the device is in folded position, one of said elements adapted for engagement with a portion of said plunger when in extended position to 60
65 effect movement of the same.

6. In a device of the class described, the combination with the plunger of a fountain pen, a supporting member, a foldable device pivotally mounted to said supporting member, co-acting elements formed on opposite ends of said foldable device for engagement with each other when the device is in folded position, one of said elements adapted for engagement with a portion of 70
75 said plunger when in extended position to effect movement of the same, and means for locking said foldable device in folded position.

In testimony whereof I have affixed my signature.

EDWARD PERINA.
